CLAIM

I claim an ornamental design for a utility trailer, as shown and described.

DESCRIPTION

FIG. 1 is a perspective view of an embodiment of a utility trailer design;

FIG. 2 is a top view of the claimed design of FIG. 1;

FIG. 3 is a bottom view of the claimed design of FIG. 1;

FIG. 4 is a right side view of the claimed design of FIG. 1;

FIG. 5 is a left side view of the claimed design of FIG. 1;

FIG. 6 is a front view of the claimed design of FIG. 1;

FIG. 7 is a back view of the claimed design of FIG. 1;

FIG. 8 shows a cross section view taken along line 8—8 in FIG. 2;

FIG. 9 is a perspective view of a second embodiment of a utility trailer design;

FIG. 10 is a top view of the claimed design of FIG. 9;

FIG. 11 is a bottom view of the claimed design of FIG. 9;

FIG. 12 is a right side view of the claimed design of FIG. 9;

FIG. 13 is a left side view of the claimed design of FIG. 9;

FIG. 14 is a front view of the claimed design of FIG. 9;

FIG. 15 is a back view of the claimed design of FIG. 9; and,

FIG. 16 shows a cross section view taken along line 16—16 in FIG. 10.
